UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING AND ASSOCIATING MECHANISM.

1,325,975.

Specification of Letters Patent. Patented Dec. 23, 1919.

Application filed May 22, 1918. Serial No. 236,021.

To all whom it may concern:

Be it known that I, HOWARD M. BARBER, a citizen of the United States, and resident of Stonington, in the county of New London and State of Connecticut, have invented a new and useful Improvement in Sheet Collecting and Associating Mechanism, of which the following is a specification.

In sheet collecting and associating mechanism it is very difficult to hold the sheets in register on the collecting and associating cylinder as the grippers open to collect the sheets and open to transfer the sheets. This is especially true where a number of sheets are to be collected and associated and transferred and where the sheets are heavy.

The object of my invention is to provide novel means for insuring the proper holding of the sheets on the cylinder against slipping out of register while being collected, associated and transferred, said means including a rotary carrier having end and side grippers which cooperate to collect a number of sheets fed from one source, such, for instance, as a source of main web sheet supply, and to combine therewith an extra sheet fed from another source, such for instance, as a cover sheet; another cylinder being provided with grippers which will associate an extra sheet fed from another source, such for instance, as an insert sheet, with the so-collected and associated cover and main web sheets.

The side grippers on the collecting cylinder serve to hold the sheets which are thereon in register when the end grippers are opened.

The side grippers open beyond the sides of the sheets as the grippers pass the several sheet collecting, associating and transfer points so as not to interfere with the passage of the sheets.

A practical embodiment of my invention is represented in the accompanying drawings in which,

Figure 1 is a view in front elevation of so much of a sheet handling machine as includes my invention.

Fig. 2 is a section taken in the plane of the line II—II of Fig. 1.

Fig. 3 is a section taken in the plane of the line III—III of Fig. 1.

Fig. 4 is a section taken in the plane of the line IV—IV of Fig. 1, and

Fig. 5 is a detail section showing one of the side grippers and one of its operating cams.

One or more webs pass over the web feed roll 1, and downwardly through the pair of coacting cutters 2, 3, and guides 4, 5, to one of three sets of grippers 6 on the main web sheet feeding cylinder 7.

The combined collecting and cover associating cylinder 8 is herein shown as provided with three sets of end grippers 9 and three sets of corresponding side grippers 10, the side grippers being located a considerable distance back of their end grippers so as to engage the sheets at about midway their length.

The cylinder 11 is an extra sheet feeding cylinder arranged to feed one or more extra sheets to each of the collecting and associating surfaces of the cylinder 8. In the present instance, this cylinder 11 is arranged to feed cover sheets to the cylinder 8 at the proper intervals to be associated with the collected main web sheets, as will hereinafter appear.

The cylinder 11 is provided with a set of end grippers 12 arranged to take the covers from a suitable feed table 13 and transfer them to the end grippers 9 of the combined sheet collecting and associating cylinder 8.

The sheet stop 14 for the sheets on the table 13 is operated by a cam 15 fixed to rotate with the cylinder 11.

An extra sheet feeding and product transfer cylinder 16 is provided with a set of grippers 17. Extra sheets, as for instance, inserts, are fed from the table 18 to the grippers 17. The sheet stop 19 for the table 18 is operated by the cam 20 fixed to rotate with the cylinder 16.

A fixed cam 21 is arranged in position to open the grippers 6 on the feeding cylinder 7 to receive the main web sheet from the rotary cutters 2, 3. A fixed cam 22 is arranged in position to open the grippers 6 to transfer the main web sheets to the end grippers 9 of the cylinder 8.

The grippers 12 of the cover feeding cylinder 11 are provided with a tumbler cam 23

controlled by the pins 24, 25 to close the grippers 12 on the cover sheets as they are fed from the table 13 to open the grippers to transfer the cover sheets to the end grippers 9 of the cylinder 8.

Each set of end grippers 9 on the cylinder 8 is opened by the engagement of the stationary cam 26 with the gripper stud or roller 27 at one end of the cylinder 8, every 10 revolution of the cylinder to collect main web sheets from the feeding cylinder 7, and is opened every one and one-third revolutions of the cylinder 8, by the engagement of the two-part movable cam 28, 29, with the 15 gripper stud or roller 30 at the other end of the cylinder 8 to first transfer its collected and associated main web and cover sheets to the grippers 17 of the cylinder 16 and to then receive and grasp a cover sheet 20 fed from the grippers 12 of the cover feeding cylinder 11. The part 28 of this two-part cam is operated by a cam 31 carried by the cylinder 16 which engages a stud roller 32 on the part 28. The part 29 of 25 the two-part cam is operated by a cam 33 carried by the cover feeding cylinder 11 which engages a stud or roller 34 on the part 29. Springs 35, 36, serve to return the parts 28, 29, of the cam to their normal positions 30 out of the path of the stud or roller 30 of the end grippers 9.

The side grippers 10 of each set on the cylinder 8 are held normally closed by springs 37 and are opened by the engagement of stationary cams 38 with the gripper studs or rollers 39 when the end grippers 9 are opened to collect the main web sheets from the feeding cylinder 7. These side grippers 10 are again opened by the cams 40 when the 40 end grippers 9 are opened to transfer the collected and associated cover and main web sheets to the cylinder 16. These last named cams 40 are sufficiently long to hold the side grippers 10 open until they pass the point 45 where their end grippers take the cover from the feeding cylinder 11. These cams 38 and 40 serve to swing the side grippers out beyond the sides of the sheets as the side grippers pass the points where the main web 50 sheets and covers are taken as well as where the collected and associated cover and main web sheets are transferred to the cylinder 16.

The end grippers 17 of the cylinder 16 are opened to receive the collected and associated main web and cover sheets on top of the insert sheet by a fixed cam 41 which engages the gripper stud or roller 42 at one end of the cylinder. These grippers 17 are also provided with a tumbler cam 43 which 55 coacts with the pins 44 and 45 to open the grippers 17 to deliver the collected and associated cover, insert and main web sheets to the folding mechanism 46, 47, and to close the grippers 17 onto the insert sheet as it is 60 fed from the table 18 thereto.

From the above description it will be seen that when a certain set of end grippers 9 on the collecting and associating cylinder 8 have been opened to transfer the collected and associated cover and main web sheets to 70 the grippers 17 of the cylinder 16, on top of the insert to be associated therewith, the cam part 29 will hold the grippers 9 open until they receive the cover from the grippers 12 of the cylinder 11, when the end 75 grippers are permitted to close on the cover and carry it around into position to receive thereon the first part of the collection of main web sheets fed from the cylinder 7. The side grippers close on the cover as the 80 end grippers open to collect and thereafter close on the sheets which are on the cylinder 8, during the several revolutions of the cylinder. These side grippers also close on the sheets as the end grippers are opened to 85 transfer the collected and associated cover and main web sheets to the cylinder 16.

In the arrangement of the parts herein shown and described, the cylinders 7 and 8 rotate one and one-third revolutions for 90 every revolution of the cylinders 11 and 16.

While I have disclosed my invention as applied to a three-way collecting cylinder arranged to collect four sheets or groups of sheets, it is obvious that I do not wish to 95 limit myself to this particular arrangement, but

What I claim is:

1. Sheet collecting and associating mechanism including web sheet cutters, a transfer cylinder and a combined collecting and associating cylinder having end grippers arranged to take one or more extra sheets and to collect the sheets fed from the cutters and to transfer the so collected and associated sheets to the transfer cylinder, side grippers arranged to hold the sheets which are on the collecting and associating cylinder as the end grippers are opened to collect and means to combine on the transfer cylinder one or more 105 extra sheets with the said collected and associated sheets.

2. Sheet collecting and associating mechanism including web sheet cutters, a transfer cylinder and a combined collecting and associating cylinder having end grippers arranged to take a cover sheet and to collect thereon sheets fed from the cutters and to transfer the so collected and associated sheets to the transfer cylinder, side grippers arranged to hold the sheets which are on the collecting and associating cylinder as the end grippers are opened to collect, and means to combine on the transfer cylinder one or more insert sheets with said collected 115 and associated sheets.

3. Sheet collecting and associating mechanism, including a combined insert sheet feeding and product transferring cylinder, a combined collecting and associating cylinder 130

having coöperating end and side grippers arranged to take a cover sheet, collect thereon main web sheets and transfer the so collected and associated sheets to the first 5 named cylinder to be combined with the insert sheet or sheets.

4. Sheet collecting and associating mechanism, including a combined insert sheet feeding and product transferring cylinder, a 10 cover feeding cylinder, a main web sheet feeding cylinder, a combined collecting and associating cylinder having coöperating end and side grippers arranged to take a cover sheet from its cylinder, collect thereon main 15 web sheets from their cylinder, and transfer the so collected and associated sheets to the first-named cylinder to be combined with the insert sheet or sheets.

5. Sheet collecting and associating mechanism, including a transfer cylinder, means 20 for feeding one or more insert sheets thereto, a cover feeding cylinder, means for feeding a cover sheet thereto, a combined collecting and associating cylinder having coöperating 25 end and side grippers arranged to take a cover sheet, collect main web sheets thereon and transfer the so collected and associated cover and main web sheets to the transfer cylinder to be combined with the insert sheet 30 or sheets thereon.

6. Sheet collecting and associating mechanism, including a transfer cylinder, means for feeding one or more insert sheets thereto, a cover feeding cylinder, means for feeding 35 a cover sheet thereto, a combined collecting and associating cylinder having coöperating end and side grippers arranged to take a cover sheet, collect main web sheets thereon, and transfer the so collected and associated 40 cover and main web sheets to the transfer cylinder to be combined with the insert sheet or sheets thereon, the side grippers on the

combined collecting and associating cylinder being arranged to hold the sheets which are thereon as the end grippers are opened to 45 collect and transfer the sheets.

7. Sheet collecting and associating mechanism, including a transfer cylinder, means for feeding one or more insert sheets thereto every revolution thereof, a cover feeding 50 cylinder, means for feeding a cover sheet thereto, every revolution thereof, a three-way combined collecting and associating cylinder having coöperating end and side grippers arranged to take a cover sheet, collect a plurality of main web sheets thereon and transfer, every one and one-third revolutions, the so collected and associated cover and main web sheets to the transfer cylinder to be combined with the insert sheet or sheets 55 thereon.

8. Sheet collecting and associating mechanism, including a transfer cylinder, means for feeding one or more insert sheets thereto every revolution thereof, a cover feeding 65 cylinder, means for feeding a cover sheet thereto every revolution thereof, a three-way combined collecting and associating cylinder having coöperating end and side grippers arranged to take a cover sheet, collect a plurality of main web sheets thereon and transfer, every one and one-third revolutions, the so collected and associated cover and main web sheets to the transfer cylinder to be combined with the insert sheet or sheets 70 thereon, the side grippers on the combined collecting and associating cylinder being arranged to hold the sheets thereon as the end grippers are opened to collect and transfer the sheets.

In testimony, that I claim the foregoing as my invention, I have signed my name this seventeenth day of May, 1918.

HOWARD M. BARBER.
